SAWMILL DOG

Filed Jan. 25, 1926

2 Sheets-Sheet 2

Fig. 2.

This technical drawing illustrates a cross-sectional view of a mechanical assembly, possibly a valve or pump mechanism. The drawing is oriented vertically, with the main body of the device on the right and various internal components and external parts labeled with numbers 1 through 53. Key labeled parts include:

- 19: A large vertical cylinder on the right side.
- 15: A piston or rod within the cylinder.
- 53: A circular component with a central hole, possibly a valve or seal.
- 52: A curved, U-shaped component, likely a lever or link.
- 17: A vertical rod or shaft.
- 26: A horizontal rod or link.
- 32: A circular component, possibly a wheel or pulley.
- 7: A small part at the bottom left.
- 10, 12, 13: Components located near the top right, possibly a set of valves or seals.
- 50: A component near the top center.
- 14: A vertical rod or shaft.
- 11, 24, 25, 26, 27, 28, 29, 30, 31, 32, 33, 34, 35, 36, 37, 38, 39, 40, 41, 42, 43, 44, 45, 46, 47, 48, 49: Various smaller components, including springs, pins, and adjustment screws, distributed throughout the assembly.

SAWMILL DOG.

Application filed January 25, 1926. Serial No. 33,438.

This invention relates to improvements in sawmill dogs of the so-called tong type. Sawmill dogs of the character referred to comprise, in general, a knee, a pair of tong arms arranged in a vertical plane transverse to the face of the knee and provided with teeth extending beyond the latter, and suitable means or mechanism for effecting movement of the tong arms toward and away from each other to grip and release the log. The tong teeth engage the upper and under sides or edges of the log or cant to securely hold the same against the face of the knee in the well-known manner. In the tong dogs constructed heretofore, the distance which the tong teeth extend outwardly beyond the face of the knee is fixed and cannot be adjusted, so that the thickness of the last board is determined by this distance which is necessarily an appreciable amount for the reason that the teeth must extend outwardly beyond the face of the knee an appreciable amount in order to get a good grip on the log. In the so-called boss dogs, provision has been made for adjusting the teeth in a direction transverse to the face of the knee, the teeth being moved outwardly to their fullest extent for holding logs and moved or adjusted to their extreme inward position with respect to the face of the knee for holding a cant or small board. In the boss dogs, however, the teeth bite into and mar the face board, which is a serious objection, particularly in the handling and sawing of valuable timber. In our copending application Serial No. 56,590, filed September 16, 1925, a sawmill dog of the tong type has been shown and described wherein the tong arms are adjustable longitudinally in a direction transverse to the face of the knee whereby the tong teeth may be moved outwardly a comparatively great distance beyond the face of the knee for holding a log, and adjusted or moved inwardly to within a comparatively small distance from the face of the knee for holding the last board. While this proposed construction has proven to be very satisfactory and represents a distinct step forward in the art, it has been found that the upper tong tooth, which is designed particularly to hold large logs, is not so well adapted or shaped to hold boards. In this improved sawmill dog, furthermore, the tong tooth does not move absolutely parallel with the

face of the knee, and while this is not objectionable in the holding of logs or cants, it does make some difference in the holding of comparatively thin boards.

One of the objects of the present invention, therefore, is to provide an improved means for holding or guiding one of the tong arms of sawmill dogs of the character referred to whereby the tooth fixed in the outer end of this arm may be adjusted in a direction transverse to the face of the knee.

Another object is to provide, in a sawmill dog of the tong type, an auxiliary tooth associated with and having a different shape than one of the tong teeth, the arrangement being such that in the dogging of comparatively small boards, the tong teeth may be withdrawn or moved inwardly to permit the auxiliary tooth, which is particularly adapted and shaped for holding these comparatively small boards, to engage and hold the same, the auxiliary tooth being guided for movement parallel to the face of the knee.

Other objects and advantages will herein-after appear.

For the purpose of illustrating the invention, an embodiment thereof is shown in the drawings, in which

Figure 1 is a side elevation of the sawmill dog shown and described in our above copending application, showing the auxiliary tooth and the improved guiding means for the upper tong arm applied thereto; and

Fig. 2 is a front elevation, looking toward the right in Fig. 1.

The upper tong arm 1, provided with the tooth 2 fixed in the cylindrical end portion 3 thereof, is pivotally mounted at its rear end on a pin 4 fixed in the upper end of an arm 5 loosely mounted on a shaft 6 journaled in the base 7 of the knee, the forward end or cylindrical portion 3 of arm 1 extending loosely through a suitable hanger 8 pivotally mounted on a bolt 9 extending through a shoe 10. Shoe 10 comprises a base 11 and an arm 12 extending outwardly therefrom at a right angle thereto, the outer end of arm 12 being provided with a downwardly extending portion 13 provided with an opening for receiving bolt 9 and which registers with a similar opening in base 11, as more clearly shown in Fig. 2. The head 14 of bolt 9 acts with the spaced members 15 and 16 to guide shoe 10 for movement

in a vertical plane and to hold the shoe in operative relation with respect to knee 17. Members 15 and 16 are secured by means of suitable screws 18 to a vertical part 19 which is fixed to one side of the knee by any suitable means such as bolts 20. An auxiliary tooth 21 is arranged below hanger 8, and fixed to base 11 of shoe 10 by means of a bolt 22, the head 23 of the latter fitting back of members 15 and 16 to act with head 14 of bolt 9 to guide shoe 10 and hold the same in operative relation with respect to the knee. Rollers 24 may be loosely fitted on bolts 9 and 22 and arranged to move between the adjacent edges of members 15 and 16 to facilitate vertical sliding movement of shoe 10. As shown in Fig. 1, the auxiliary tooth 21 is of a different shape than the tong tooth 2 and is particularly adapted to engage the upper edge of the comparatively small board 25 to hold the same securely against the face 26 of the knee, the auxiliary tooth 21 extending only a small distance outwardly beyond the knee face so that the last board may be comparatively thin.

A lever 27 is loosely mounted on shaft 6 and connected by means of an arm 28 to an eccentric sheave 29 mounted on an eccentric 30 fixed to a shaft 31, the latter being rotated in either direction by means of a reversible electric motor 32 connected thereto in any suitable manner. Lever 27 is provided at the upper end thereof with an adjustable bolt 33 engaging the adjacent rear edge of arm 5, a bolt 34 extending through an opening in a pin 35 carried by arm 5 and being pivotally connected at 36 to lever 27, a spring 37 being arranged on bolt 34 and compressed between pin 35 and nuts 38 threaded upon the end of bolt 34, whereby arm 5 is connected to lever 27 for movement therewith. The lower tong arm 39 is pivotally connected at its rear end to a link 40 connected to a crank pin 41 fixed to a block 42 keyed to shaft 31. The forward end of tong arm 39 is provided with a tooth 43 and is loosely fitted in a shoe 44, a bolt 45 extending loosely through this shoe and being provided with a head 46 fitting back of members 15 and 16 for the purpose of guiding the shoe for vertical movement and holding the same in operative relation with respect to knee 17. A roller 47, similar to rollers 24, may be loosely arranged on bolt 45 between members 15 and 16.

A rack 48 is pivotally connected to lower tong arm 39 by means of a pin 49 and extends upwardly through a housing 50 supported for pivotal movement on a shaft 51 journaled in bearings 52 with which the upper tong arm 1 is provided at each side thereof, a pinion (not shown) being fixed to shaft 51 and being arranged in mesh with the teeth of rack 48 so that the tong arms

1 and 39 may be moved toward or away from each other upon rotation of shaft 51 in the desired direction by means of a reversible electric motor 53 connected to shaft 52 in any suitable manner.

The operation of the improved sawmill dog is as follows: In dogging a log, motor 32 is operated to rotate shaft 31 in a counter-clockwise direction to effect rotary movement of lever 27 in this direction about shaft 6, bolt 33 engaging the rear edge of arm 5 to move upper tong arm 1 forward so that the tong tooth 2 moves forward a substantial distance in a direction transverse to the face 26 of the knee to the dotted line position, which position is determined by the engagement of the stop bolt 54 with block 42. This forward movement of the upper tong arm is accompanied by a similar movement of lower tong arm 39, the sliding fit of the forward end of this arm in shoe 44 permitting this movement of the arm to project the tong tooth 43 a substantial distance beyond the face of the knee to the dotted line position. The motor 53 is then operated in the usual manner to effect movement of the tong arms toward each other to grip or hold the log. When it is desired to saw a thin board, motor 53 is reversed to withdraw the tong teeth 2 and 43 to the respective positions thereof shown in full lines, which positions are determined by engagement of the stop bolt 55 with block 42, the arrangement being such that tooth 2 is completely withdrawn to a position to the right of the knee face 26, as shown, the lower tong tooth 43 extending outwardly beyond the face of the knee a comparatively small amount equal substantially to the amount or distance which auxiliary tooth 21 extends beyond the face of the knee, as shown. The lower end portion of members 15 and 16 are parallel to face 26 of the knee, so that the auxiliary tooth moves parallel therewith.

From the foregoing it will be seen that shoe 10 and hanger 8 supported thereby provide means for supporting the upper tong arm 1 and permit longitudinal sliding movement or adjustment thereof in a direction transverse to the face 26 of the knee whereby tong tooth 2 may be projected or extended outwardly to the dotted line position shown, or completely withdrawn, as shown in full lines, to permit auxiliary tooth 21 to engage the upper edge of board 25 and to cooperate with tooth 43 to hold the latter securely against the face of the knee, the advantages of the tong tooth 2 thus being obtained in the holding of logs and the advantages of the auxiliary tooth 21 being obtained in the holding of comparatively small timber and boards.

The various other parts of the sawmill dog, such as the driving connections between

motor 53 and shaft 51 and between motor 32 and shaft 31, are shown and described in detail in our above copending application, and have only been shown and described above in sufficient detail to enable those skilled in the art to understand the manner of embodying the construction constituting the present invention in a sawmill dog of the tong type, such as is shown in our said application.

A preferred embodiment of the invention has been shown and described, but of course various changes in the size, shape and arrangement of the parts may be adopted without departing from the spirit of the invention or the scope of the claims.

The invention claimed is:

1. In a sawmill dog, a knee having a vertical face, a shoe, a hanger, a bolt connecting said shoe and hanger for pivotal movement with respect to each other and arranged with its head engaging said knee to guide said shoe and hanger for movement parallel to the knee face, a log-holding arm supported for pivotal movement in a vertical plane and arranged with its log-engaging end extending loosely through said hanger and beyond the knee face, and means operable to effect said pivotal movement of said arm.

2. In a sawmill dog, a knee, a shoe, means for constraining the shoe to adjustments up and down in a vertical plane, a log-holding arm having a log-holding tooth at its outer end portion, means for positively interconnecting the shoe and said arm to constrain the shoe to move up and down vertically with the arm while permitting the arm to be adjusted independently of the shoe inwardly and outwardly with respect to the knee, means cooperable with the arm for moving the same up and down in a vertical plane whereby the shoe is also moved up and down in a vertical plane, and an auxiliary tooth fixed to the shoe so as to partake of the vertical movements thereof under the influence of the arm, said auxiliary tooth being designed to engage a faced log or board.

3. In a sawmill dog, a knee having a face, a log-holding arm having a log-engaging tooth at its outer end, means for constraining the log-holding arm to partake of up and down movement in a vertical plane and in and out translatory movement transverse to the knee face, means cooperable with said log-holding arm for moving it up and down in a vertical plane and an auxiliary tooth constrained to move vertically and parallel to the face of the knee under the influence of the log-holding arm and designed to engage a faced board or log.

4. In a sawmill dog, a knee having a vertical face, a log-holding arm arranged transversely of the knee face and supported at its rear end for pivotal movement in a

vertical plane and about a relatively fixed axis, a shoe, means extending laterally from said shoe and engaging said knee to guide said shoe for movement parallel to the knee face, a hanger slidably receiving and supporting the log-engaging end of said arm and carried by said shoe for vertical movement therewith and pivotally connected thereto to permit tilting of said hanger upon vertical movement of said arm about said axis simultaneously with similar movement of said shoe parallel to the knee face, and means operable to cause said pivotal movement of said arm.

5. In a sawmill dog of the tong type, a knee having a face, a shoe associated with said knee for vertical movement with respect thereto and comprising a base and an arm extending outwardly from said base at one end thereof and provided with a downwardly extending portion, a member arranged between said base and said portion, said member and said base and said portion being provided with registering openings, means extending through said openings for holding said shoe and member in assembled relation, an arm arranged transversely of the knee face and extending loosely through said member, said arm being provided with a tooth at the outer end thereof, and means for causing sliding movement of said arm with respect to said member whereby said tooth may be adjusted with respect to the knee face.

6. In a sawmill dog, a knee, a log-holding arm having a log-engaging tooth and arranged with said tooth disposed adjacent the knee face, means supporting said arm for rotary movement in a fixed vertical plane and for bodily movement in said plane in a direction transverse to the knee face to adjust said tooth varying distances with respect to the later, means operable to impart said movements to said arm, and an auxiliary tooth extending outwardly beyond the knee face and guided and supported for movement parallel thereto and for movement with said arm in said vertical plane, said auxiliary tooth being operable to engage a faced log upon bodily movement of said arm in said plane to its respective position of adjustment to place said first-named tooth inwardly beyond the knee face.

7. In a sawmill dog, a knee having a vertical face, a shoe, a hanger, a bolt connecting said shoe and hanger for pivotal movement with respect to each other and arranged with its head engaging said knee to guide said shoe and hanger for movement parallel to the knee face, a log-holding arm supported for pivotal movement in a vertical plane and arranged with its log-engaging end extending loosely through said hanger and beyond the knee face, an auxiliary tooth carried by said shoe and projecting beyond the

- knee face short of the range of operation of said log-engaging end and disposed in such wise as to engage a faced log upon movement of said arm with respect to said hanger 5 to position its log-engaging end inwardly with respect to the knee face, means for imparting said last-named movement to said arm, and means operable to effect said pivotal movement of said arm.
- 10 8. In a sawmill dog, a knee having a vertical face, a log-holding arm arranged transversely of the knee face and supported at its rear end for pivotal movement in a vertical plane and about a relatively fixed axis, a 15 shoe, means extending laterally from said shoe and engaging said knee to guide said shoe for movement parallel to the knee face, a hanger slidably receiving and supporting the log-engaging end of said arm and carried by said shoe for vertical movement 20
- therewith and pivotally connected thereto to permit tilting of said hanger upon vertical movement of said arm about said axis simultaneously with similar movement of said shoe parallel to the knee face, an auxiliary tooth carried by said shoe and projecting beyond the knee face short of the range of operation of said log-engaging end and disposed in such wise as to engage a faced log 25 upon sliding movement of said arm with respect to said hanger to position its log-engaging end inwardly with respect to the knee face, means for imparting said last-named movement to said arm, and means operable to cause said pivotal movement of 30 said arm.
